UNITED STATES PATENT OFFICE

RAYMOND E. DE WALT, OF LEOILA, PENNSYLVANIA, ASSIGNOR TO DE WALT PRODUCTS COMPANY, OF LEOILA, PENNSYLVANIA, A COPARTNERSHIP CONSISTING OF ISAAC LICHTY BUTT AND CLARENCE PAUL GARDNER

WOODWORKING MACHINE

Application filed May 10, 1926. Serial No. 108,140.

This invention relates to a woodworking machine of the type disclosed in my Patent No. 1,528,536 granted on March 3, 1925, in which a horizontal arm is adjustably carried on a post and a woodworking tool is mounted on a slide movable along the arm. In the patented machine the tool is supported in a yoke, the upper end of which is mounted for angular adjustment in the slide by having a square-headed bolt secured to the yoke and fitting in a square hole in the slide. The object of the present invention is to provide a more efficient angular adjustment in which the parts are held in place by a cam locking bolt.

While I have disclosed a commercial form of the invention for purposes of illustration, it should be understood that the structure may be modified in various ways without departing from the true spirit and scope of the invention as hereinafter defined and claimed.

In the drawings;

Fig. 1 is a side elevation of a machine embodying the invention;

Fig. 2 is an end elevation of the vertical arm and slide block looking from left of Fig. 1.

Fig. 3 is a section on line 3—3 of Fig. 2;

Fig. 4 is a section on line 4—4 of Fig. 3.

Referring to the drawings more particularly, the horizontal arm 10 is pivoted on the post 11 and can be locked in any desired angular position by the nut 12. The socket 13 fastened to table 14 slidably carries the post 11, rotation of the post being prevented by a set screw 15 fitting into a key-way 16 formed in the post. Vertical adjustment of the post is effected by rotating screw 17 by means of handle 18.

The horizontal arm 10 is provided with a track 19 in which slides the carriage 20. A projection 21 extends from the lower side of the carriage and is formed with a lateral supporting flange 22 perforated by holes 23 located 90° apart. The yoke 24, in which the woodworking tool is adjustably mounted, carries at its upper part a cup 25. A two-part cover-flange 26 which is fastened to the cup by bolts 27, extends over the flange 22 and

carries two pins 28 extending into opposite holes 23.

A bolt 29 extends through a vertical opening 30 in the carriage and is screw-threaded into the yoke 24, being anchored by a lock screw 31. Near its upper end the bolt 29 is formed with a reduced portion 32. A horizontal bore 33 extends through the carriage from its front end to the opening 30 and a locking bolt 34 is rotatably mounted in the bore. A set-screw 35 extends into a key-way 36 formed on the bolt. The inner end of the locking bolt carries a cam 37 fitting into the reduced portion 32 of the bolt 29, while its outer end is formed into a handle 38.

A set-screw 39 is mounted on the carriage and engages the track to hold the slide in any desired position along the track.

When the parts are in the position illustrated in Figs. 2 and 3 the cam 37 is pushing downwardly upon the bolt 29, thereby pressing the yoke 24 and its attached flange 26 downwardly. This action clamps the flange 26 firmly against the flange 22 and holds the pins 28 in holes 23. When it is desired to change the angular position of the yoke with respect to the horizontal arm the handle 38 is moved in a counter-clockwise direction as seen in Fig. 2, thereby moving the bolt 29 upward and lifting flange 26 to disengage the pins 28 from holes 23. The yoke may now be moved to any angular position with the pins 28 registering with a pair of the holes 23 and the handle 38 is then moved in a clockwise direction to lock the yoke and the tool carried thereby in the new position.

In the yoke 34 is swingingly supported a motor 40 driving a wood working tool such as the saw 41.

With this construction the tool 41 cannot only be moved in and out on the arm but can be positioned longitudinally of the arm or transverse thereof. Moreover, the tool may be raised from the slot or curve cut by manipulation of the handle 38 without turning the tool on the axis of the shaft 32, if desired.

It will be evident that the device herein disclosed provides a very positive and efficient means for holding the woodworking tool in

the desired position, since the engaging flanges give a firm support when rigidly locked together by the cam bolt. At the same time the structure readily lends itself to commercial production.

5 I claim:—

1. In a woodworking machine, a tool supporting arm, a carriage slidable along said arm, a vertical shaft slidably and rotatably mounted in said carriage, a yoke fixed to the lower end of said shaft, a woodworking tool mounted in said yoke, a cam member having a shaft journaled in said carriage and movable therewith, said cam member being arranged to raise and lower said shaft and yoke, and coacting means on the carriage and yoke holding the first shaft from rotation upon the yoke being in lowered position, and freeing from each other upon the yoke being raised, to permit rotation of said first shaft.
- 10 2. In a woodworking machine, a tool supporting arm, a carriage slidable along said arm, a vertical shaft slidably and rotatably mounted in said carriage, a yoke fixed to the lower end of said shaft, a woodworking tool mounted in said yoke, a cam member having a shaft journaled in said carriage and movable therewith, said cam member being arranged to raise and lower said shaft and yoke, pins supported from said yoke, and a flange fixed on said carriage having openings in which said pins engage upon the yoke being lowered.
- 15 3. In a woodworking machine, a tool supporting arm, a carriage slidable along said arm, a vertical shaft slidably and rotatably mounted in said carriage, a yoke fixed to the lower end of said shaft, a woodworking tool mounted in said yoke, a cam member having a shaft journaled in said carriage and movable therewith, said cam member being arranged to raise and lower said shaft and yoke, a boss depending from said carriage in which the first shaft is journaled, a flange extending laterally from the lower end of said boss and provided with circularly spaced pin receiving openings, and pins supported from said yoke to engage and disengage said openings as the yoke is raised and lowered.
- 20 4. In a woodworking machine, a tool supporting arm, a carriage slidable along said arm, a vertical shaft slidably and rotatably mounted in said carriage, a yoke fixed to the lower end of said shaft, a woodworking tool mounted in said yoke, a cam member having a shaft journaled in said carriage and movable therewith, said cam member being arranged to raise and lower said shaft and yoke, a boss depending from said carriage in which the first shaft is journaled, a flange extending laterally from the lower end of said boss and provided with circularly spaced pin receiving openings, a flange extending upwardly from the yoke and fitting around the first

flange, an annular plate surrounding said boss and having its outer part projecting over the second flange and secured thereto, and pins projecting downwardly from said plate to enter the openings in the first flange upon the yoke being lowered.

5 6. In a woodworking machine, a tool supporting arm, a yoke mounted on said arm, a woodworking tool mounted in said yoke, vertically engaging means carried by the yoke and arm to position said yoke about a vertical axis relative to said arm, and a cam member operative to raise the yoke to disconnect the engaging means to permit rotation of the yoke about said vertical axis to a different position.

In testimony whereof I affix my signature.

RAYMOND E. DE WALT.
